(57) **CLAIM**

The ornamental design for a luggage bag as shown and described.

DESCRIPTION

FIG. 1 is a top, front, right side perspective view of a luggage bag showing my new design;

FIG. 2 is a bottom, rear, left side perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a perspective view of the luggage bag shown in an alternative configuration with the top opened and the pull rod extended;

FIG. 10 is a perspective view of the luggage bag shown in another alternative configuration with the top opened and the pull rod extended; and,

FIG. 11 is a perspective view of the luggage bag shown in an alternative configuration with the strap taken out and buckled.

The broken lines in the drawings depict portions of the luggage bag that form no part of the claimed design.

1 Claim, 11 Drawing Sheets
